UNITED STATES PATENT OFFICE.

WILLIAM C. CUTLER, OF LOS ANGELES, CALIFORNIA, AND EMANUEL J. BOYLER, OF NEW HAVEN, CONNECTICUT, SAID BOYLER ASSIGNOR TO SAID CUTLER.

DIRECTORY-CABINET.

1,120,910.

Specification of Letters Patent. Patented Dec. 15, 1914.

Application filed June 1, 1914. Serial No. 842,152.

To all whom it may concern:

Be it known that we, WILLIAM C. CUTLER, residing at Los Angeles, in the county of Los Angeles and State of California, and 5 EMANUEL J. BOYLER, residing at New Haven, in the county of New Haven and State of Connecticut, both citizens of the United States, have invented a new and useful Directory-Cabinet, of which the following is a specification.

This invention relates to directory cabinets, and the object of the invention is to dispense with a movable curtain and provide a rigid board provided with the required directions for operation.

A further object is to simplify and reduce the number of parts of the operating mechanism.

Another object is to provide a glass plate 20 around the dial to protect the index information underneath, and to provide an index by which the various sub headings under a certain city or district may be obtained.

Another object is to provide for operating the movement of the directory card by the weight of a person standing on a platform instead of operating a hand lever, as heretofore.

Another object is to provide a novel frame for each card to support the card properly and rigidly.

Another object is to provide for cushioning the movements of the mechanism so the 35 device will operate smoothly.

Referring to the drawings: Figure 1 is a perspective view of the complete machine. Fig. 2 is a vertical longitudinal section through the machine. Fig. 3 is a section on line x^3-x^3 , Fig. 2. Fig. 4 is an enlarged section taken diametrically through the index dial. Fig. 5 is a section enlarged on line x^5-x^5 , Fig. 2. Fig. 6 is an elevation of the latch mechanism looking in the direction of the arrow x^6 , in Fig. 5. Fig. 7 is a plan view of the dial and glass plate. Fig. 8 is a perspective view of the card frame and selectors.

The device comprises a cabinet 1 with 50 transparent panel 2 behind which is a stationary board 3, upon which is printed the necessary directions for operating the device, this board being visible at all times except when a directory card is in view in front of it. A series of indicating cards 4

are provided, each of which is contained in a suitable frame 6 and provided with short rods 7 at the upper end thereof, these rods resting between pins 8, which project from steel straps 9 running over lower pulleys 10, 60 intermediate pulleys 11 and upper pulleys 12, the angle of the tapes between pulleys 8 to 12 being such that the cards 4 are permitted to hang straight down parallel with each other without interference, so that a 65 large number of cards may be kept in compact arrangement in this space. The pulleys 10 are revolved by a cable 13, which is wound on a hub 14, then passes over idlers 15", and thence to the pulleys 10', passing 70 onto pulleys 10' from opposite sides; pulleys 10 and 10' are fixed on shaft 54. The hub 14, as clearly shown in Fig. 4 is carried by a shaft 15, to which is fixed a dial 15' 75 having a handle 16 with a spring pressed button 17, which has a pointed lower end 18. The dial 15' revolves in a stationary table 19, and an oscillative plate 20 is mounted below the table 19 and is provided with perforations 21. Below the oscillative plate 80 20 is a stationary plate 22 provided with perforations 23. The oscillative disk 20 is normally held turned at a slight angle with the respective plate 22 so that the perforations 21 and 23 are slightly out of register, 85 and by depressing the button 17, the pointed end 18 will slightly rotate the oscillative disk 20 to bring its perforation 21 into perfect register with the perforation 23, immediately below it. The perforation will then 90 act to lock the parts in perfect alinement and hold them locked in this position during the movement of an indicating card as hereinafter described. Above the table 19 is an index sheet 24, which may be of paper or 95 other material which will contain the names of cities or other districts together with certain sub-divisions thereof, and the dial 15' may be turned to bring it into registration with any sub-division of a district on the 100 index 24. The index paper 24 is covered by two plates of glass 25, which protect the same without obscuring the index. For example, the index paper 24 may be divided off segmentally into different cities, and 105 each of those segments in turn may be subdivided into segmental sub-divisions, which may stand for any data required, as, for example, the segmental sub-divisions may stand for a professional directory, as doc- 110

tors, lawyers, etc. Thus, a stranger in New York city desiring the services of a dentist would turn the dial 15' to bring the button in line with the New York segment, and to the sub-division under the New York segment, which represents dentists. He would then press down on button 17, which would swing the oscillative disk 20 and would lock the parts in this position. During this turning of the disk 15', the hub 14 would act through the cable 13 and rotate the pulleys 10', thereby operating the tapes 9 and bringing the corresponding directory card 4 containing the dentists of New York city into central position ready for lifting into view.

A pair of ribbons extend over pulleys 27 and down in front of the board 3, and are provided with hooks 28 on their lower ends, which are provided to hook onto the short rods 7 of the card 4. The ribbons 26 after passing over the pulleys 27 extend down back of the board 3, as shown in Fig. 3, and are connected to a cross rod 29, which is connected to a block 30 slidable in a guide 31 on the back of the board 3. The guide 30 serves to hold the rod 29 in proper alignment, and give an even pull on the straps 26. A flexible connection 32 is connected to the block 30 and passes over a sheave 33, and thence over a sheave 34, and then is connected to a lever 35, the other end of the lever 35 being connected by a link 36 with an arm 37 on an operating rod 38.

39 is a dash pot for cushioning the stroke 35 of the rod 38. The rod 38 has a hook 40 to which is connected an extension spring 41, and its lower end is connected to a hook 42, which projects from a rod 43, the latter having a pin 44, which slides in a slot 45 in the rod 38. The lower end of rod 43 has a slot 46 engaged by a pin 47 on a link 48, which is pivoted to a lever 49, there being a link 50 extending from the lower end of lever 49 to an oil dash pot 51.

52 is a platform connected by suitable mechanism with lever 49' for swinging down the rear end of lever 49 whenever a weight is on the platform 52.

53 is a counter weight projecting from shaft 54 on which the pulleys 10 are mounted, which, when the parts are in normal position, stands as shown in Fig. 2, and maintains all of the connections taut.

A detent 55 on the rod 38 is normally engaged by a sliding bolt 56, and the bolt 56 as shown in detail in Fig. 6 is connected with a bell crank lever 57 pivoted at 58. The other arm of bell crank 57 is connected to a rigid arm 59, which extends from the oscillative disk 20 before referred to. A tension spring 60 tends to normally hold the bolt 56 under the detent 55.

The indicator card having been selected as before described, the operator when standing on platform 52 has pulled down

the link 49', and the link 49 has pulled down the rod 43 the length of the slot 45 and stretched the spring 41, but the rod 38 has not been drawn down because the detent 55 is engaged by the bolt 56. When, however, 70 the proper selection has been made, and the operator presses on the button 17, the pressure of the button shifts the oscillative disk 20, and its arm 59 pulls on bell crank 57 and withdraws bolt 56 from detent 55, 75 whereupon spring 41 contracts and pulls down the rod 38, and as rod 38 is pulled down it draws lever 35 and the latter drawing on cable 32 pulls down rod 29 at the rear of board 3, and pulls up the front 80 portions of straps 26 and their hooks 28 lift the card 4, which is attached thereto into view at the respective opening. When the operator steps off from the platform 52, the spring 41 contracts, and the check 51 85 restores the parts, lifting the rod 43, in turn lifting rod 38 and spring 60, restoring bolt 56 under detent 55.

What we claim is:

1. In a directory device, a series of cards, 90 a pair of belts with projections thereon, said cards having projections engaging in the projections on the belts and hanging between the belts, said belts standing at an angle to permit the cards to hang parallel, 95 a platform, a dial with means operated by the dial for bringing any of the cards into lifting position, and means operated by the platform for lifting a card off said belt when in lifting position and into view. 100

2. In a directory device, a series of cards, a pair of belts with projections thereon, said cards having projections engaging in the projections on the belts and hanging between the belts, said belts standing at an 105 angle to permit the cards to hang parallel, a platform, a dial with means operated by the dial for bringing any of the cards into lifting position, means operated by the platform for lifting a card off said belt when in 110 lifting position and into view, pulleys over which said belts pass, a shaft supporting said pulleys and a counter balance on said shaft.

3. In a directory device, a series of cards, 115 a pair of belts with projections thereon, said cards having projections engaging in the projections on the belts and hanging between the belts, said belts standing at an angle to permit the cards to hang parallel, 120 a platform, a dial with means operated by the dial for bringing any of the cards into lifting position, means operated by the platform for lifting a card off said belt when in lifting position and into view, a frame 125 around each indicating card, said frame being provided with a short rod at each upper end adapted to be engaged by said lifting means.

4. In a directory device, a series of direc- 130

tory cards, dial controlled means for bringing any of said cards into lifting position, a platform, means operated by the platform for lifting a card from lifting position into view, an oil dash pot for cushioning the stroke of said lifting means, and another fluid check for restoring said parts.

5. In a directory device, a cabinet provided with a sight opening, a stationary board behind said opening, a guide on the back of said board, the front of said board containing directions for operating the machine, a block sliding in said guide, straps passing down in front of said board and provided with card lifting devices, a series of directory cards, dial means for moving any of said cards into lifting position, a platform, and means operated by the platform for pulling on said straps to lift the selected 20 card into view in front of said board.

6. In a directory device, a cabinet provided with a sight opening, a stationary board behind said opening, a guide on the back of said board, the front of said board containing directions for operating the ma-

chine, a block sliding in said guide, straps passing down in front of said board and provided with card lifting devices, a series of directory cards, dial means for moving any of said cards into lifting position, a platform, a rod connected with said platform means, another rod having a slotted connection with the first rod, an extension spring connecting the two rods, a detent on the second rod, manually controlled means on the dial for detachably engaging said detent, said spring acting to shift the second rod when the detent is released, a lever connected with the second rod, a cable connected to said lever, and a rod connecting 30 said lifting straps, the other end of the cable being connected to said rod.
